UNITED STATES PATENT OFFICE

94,781

DESIGN FOR A HOLDER FOR CIGARETTES OR THE LIKE

Edward T. Schlender, Chicago, Ill.

Application July 27, 1934, Serial No. 52,717

Term of patent 3½ years

To all whom it may concern:

Be it known that I, Edward T. Schlender, a citizen of the United States, residing at Chicago, in the county of Cook and State of Illinois, have invented a new, original, and ornamental Design for a Holder for Cigarettes or the Like, of which the following is a specification, reference being had to the accompanying drawing, forming part thereof.

The drawing is a perspective view of a holder for cigarettes or the like showing my new design.

I claim:

The ornamental design for a holder for cigarettes or the like, as shown.

EDWARD T. SCHLENDER.
